HOLDER FOR PLUG TYPE ELECTRIC FUSES

Douglas F. Linsley, Westport, Conn., assignor to Linsley Incorporated, Westport, Conn., a corporation of Connecticut

Application September 2, 1954, Serial No. 32,138

Term of patent 14 years

(Cl. D80—1)

Fig. 1.

Fig. 2.

Fig. 3.

To all whom it may concern:

Be it known that I, Douglas F. Linsley, have invented a new, original, and ornamental Design for Holder for Plug Type Electric Fuses, of which the following is a specification, reference being had to the accompanying drawing, forming a part hereof.

Fig. 1 is a perspective view of a holder for plug type electric fuses, showing my new design;

Fig. 2 is a side view thereof, and

Fig. 3 is a transverse section substantially on line 3—3 of Fig. 1.

I claim:

The ornamental design for a holder for plug type electric fuses, substantially as shown.
